UNITED STATES PATENT OFFICE.

GLENN E. EDMUNDS, OF COLUMBUS, OHIO, ASSIGNEE TO THE BONNEY-FLOYD COMPANY, OF COLUMBUS, OHIO, A CORPORATION OF OHIO.

MINE CAR.

Application filed December 28, 1926. Serial No. 157,551.

This invention relates to cars, and more particularly to cars of the class used in coal mines and industrial plants.

The invention has to do with improvements in cars of the general construction shown in the patent to Edmunds, 1,525,072, granted February 3, 1925, the improvements relating to (1) the truck, (2) the structure of the body and its frame, and 10 (3) the wheel mounting.

An object of the invention is to provide a mine car which has a relatively low center of gravity and a high load capacity for its weight and overall dimensions.

15 In other words, the invention seeks to maintain the weight and overall dimensions of the car within reasonable limits, and to provide extremely high load capacity.

Another object of the invention is to provide 20 a car of simple and rugged construction, the parts of which may be readily manufactured and assembled. As is well known, these cars are subjected to rough usage, and must withstand severe strains.

25 Moreover, when used in coal mines, they must travel in rooms or entries which are comparatively low and narrow, and this condition prohibits increasing the height or width of the car beyond certain fixed limits.

30 In the accompanying drawings, there is shown a preferred embodiment of the invention, and in these drawings:

Figure 1 is a longitudinal sectional view.

Figure 2 is a bottom plan view.

35 Figure 3 is a perspective of the truck before the body is applied thereto.

Figure 4 is a fragmentary transverse section taken approximately through one of the wheels with the wheels shown in elevation.

40 Figure 5 is a top plan view of one of the inner truck sill bars or castings.

Figure 6 is an outer side elevational view of one of the inner sill castings.

45 Figure 7 is an end elevational view with the end wall of the body removed, showing a body structure modified somewhat in the connection of the side walls.

Figure 8 is a view similar to Figure 7, 50 showing another way of securing the side walls.

Figure 9 is a fragmentary longitudinal sectional view showing a somewhat different floor construction.

Figure 10 is a view similar to Figure 9, 55 showing still another floor construction.

The car comprises, broadly, two units, namely, a truck unit T (Fig. 3) having wheels independently mounted on stub axles, and a body unit B, which may be 60 formed with the truck in the construction of the car, or separately formed and then mounted on the truck.

It will be understood, of course, that although the parts are referred to as units, 65 they are described in this manner simply for convenience, and this mode of description is not to be interpreted as limiting the invention to a car in which the body and truck are separately formed or are separa- 70 ble from one another, as units.

Referring to the truck unit (Figure 3) the same comprises side sills or bars which are preferably cast, and are arranged in pairs at opposite sides of the truck. Wheels 75 10 are positioned between each pair of sill bars and are mounted upon stub axles 11. In the present instance, the sill bars of each pair are cast separately, and in the drawings, 12, 13, designate the outer members 80 of each pair. These sill bars are connected by cross girts, which extend through the inner sill bars to which they are secured, to the outer sill bars to which they are also secured. 85

The cross girts in the present instance, comprise a central channel beam 17 and end beams or cross bars 18, which are preferably of angular form in cross section.

The end cross girts are arranged outside 90 the wheels, and are supported upon longitudinally extending shoulders of the lugs 12', 13', 14' and 15', which constitute cut-away portions at the ends of the sill bars. These lugs or shoulders extend longitudinally of the sill bars, and are arranged in substantially the same plane with the central cross girt 17 so that the end cross bars 95 may serve to support the floor of the car in a plane below the top surfaces of the sill 100 bars or castings.

As illustrated in Figures 1 and 3, the end beams are of angular cross section, having a horizontal flange resting upon the legs 12', 13', 14', 15' and a vertical flange extending downwardly at the ends of these lugs. 105

An additional floor supporting means is

provided in the form of inwardly projecting webs or platform members 19, formed or cast integrally with the inner sill bars and arranged in substantially the same horizontal plane with the cross beams 17, 18. The truck as thus constructed, is adapted to receive the body unit which comprises, generally, a floor 20, (Figs. 1, 3 and 4) bolted or otherwise secured to the cross beams 17, 18 and to the supporting webs 19 extending inwardly from the two inner sill bars. These sill bars are cast with imperforate inner faces 22 so as to provide with the floor plate 20, an extended pocket centrally disposed between the castings and increasing substantially the car capacity, as well as lowering its center of gravity. The spaces between the sill bars are closed by means of wheel hoods 23, which, preferably, are cast to provide a rigid durable construction adapted also to serve as a bracing means for the car side walls. For this purpose, the hoods have integrally formed thereon, laterally extending webs 24 adapted to serve as attaching means for side wall braces 25 extending upwardly and laterally. In order to increase the width of the car, and provide a lateral floor extension beyond the outer sill bars 12, 13, angle members 26 are secured, as by riveting, or otherwise, to the side faces of the outer sill bars and have laterally or outwardly extending horizontal flanges 27 (Fig. 4) to which may be secured outwardly extending floor plates 28. These floor plates 35 are joined by an angle iron 29 to the side walls 30, which are reinforced by the braces 25. At each end of the car, the floor is provided with an extension plate 31, which is supported by cross beams 18 and by transverse channel or angle members 32 joined at their ends to the side angle or channel members 26.

It will be understood that the side channel members 26 and the end transverse channels 32, constitute a body base frame structure which is supported from the truck by the connection of the side channels with the outer sill castings. The body end walls may be of any suitable construction, and one of the same may be hinged, if desired, to provide a gate.

Referring to Figure 7, there is shown a somewhat modified structure in that the side walls 30' are joined to the lateral extensions 28' of the floor by means of channel members 29' instead of the angle 29 illustrated in Figure 4.

The construction illustrated in Figure 8 shows the angle 29" corresponding to the angle 29 (Fig. 4) arranged outside the body instead of interiorly thereof.

In Figures 9 and 10 there is shown somewhat varied body constructions wherein the central floor plate 20' is arranged beneath the integral supporting lugs 19 on the inner

sill bar castings 14, 15 and beneath the end cross beams 18' which, instead of having their horizontal flanges arranged above the lugs 12', 13' etc., are arranged so that the horizontal flanges are positioned beneath the lugs 12', 13', 14', 15' with the vertical flanges extending over the end surfaces of the lugs. With this arrangement, the floor extension plates 31 are secured to the central plate 20' beneath the horizontal flange of the cross beam 18'.

Figure 10 illustrates still another modification different from that illustrated in Fig. 9, in that the cross sectional shape of the end beam 18' is varied. In this instance, a T-beam 38 is secured to the longitudinally extending lugs 12', 13', etc., and has flanges 38', 38" extending horizontally in opposite directions having secured thereto, respectively, the extension plates 31 of the floor and the central floor plate 20'.

Referring to the wheel mounting shown most clearly in Figures 4, 5 and 6, it will be understood, of course, that any suitable construction may be utilized for mounting the wheels, although the stub axle type of structure is preferred with a truck of the character disclosed. Each sill casting is formed with inverted substantially U-shaped axle recess 40, open at its lower end to permit the axle 11 to be fitted therein. When a non-rotating stub axle is received, the upper end 41 of each recess 40 may be curved to form a semi-circular clamping element or half bearing adapted to cooperate with a half bearing 42 formed on a saddle member which is provided with a transversely extending securing element 43 extending across the open end of the recess 40, and having openings adapted to receive downwardly projecting lugs 44. The lugs 44 have transverse openings 48 into which may be inserted securing bolts 46 adapted to retain the saddle element and half bearing in position.

As illustrated in the drawing, this wheel mounting is utilized with a stub axle of the fixed or non-rotating type, and as will be understood, the wheel has fitted therein a roller or ball bearings (not shown). When it is necessary to drop a wheel for replacement of the axle or repair of a bearing, it is simply necessary to release the securing bolts, and by lowering the saddle member, the axle may be removed with its wheel. It will be understood that the axle is of the hollow lubricant containing type, a detachable lubricant filling 49 being provided at its end and being adapted for removal, if necessary, when the axle is to be dropped.

It will be understood, of course, that the construction illustrated and described in detail may be varied materially without departing from the invention, which is defined in the following claims.

I claim:

1. In a mine car, a truck comprising spaced sill bars at each side, wheels positioned between said sill bars and wheel hoods positioned over said wheels, said hoods each having a marginal flange secured to the sill bars and a wall-brace securing means formed integrally therewith.
2. In a mine car, a truck comprising spaced sill bars at each side, wheels positioned between said sill bars and wheel hoods positioned over said wheels, said hoods each having a marginal flange secured to the sill bars and a wall-brace securing web extending laterally therefrom.
3. In a mine car, a truck comprising spaced sill bars at each side, wheels positioned between said sill bars and cast wheel hoods positioned over said wheels, said hoods each having a marginal flange secured to the sill bars and a wall-brace securing web extending laterally therefrom.
4. In a mine car, a wheel hood having a marginal base securing flange and a laterally projecting web adapted to serve as a securing means for a wall brace.
5. In a mine car, a cast wheel hood having a marginal base securing flange and a laterally projecting web adapted to serve as a securing means for a wall brace.
6. In a mine car, a truck unit comprising a pair of sill bars at each side, wheels between said sill bars, cross bars connecting said pairs of sill bars, the end of said sill bars being shouldered in a different plane from the tops of the sill bars to receive some of said cross bars.
7. In a mine car, a truck unit comprising a pair of sill bars at each side, wheels between said sill bars, cross bars connecting said pairs of sill bars below the plane of the top surface of said sill bars and adapted to support a car floor, the ends of said sill bars being shouldered to receive some of said cross bars.
8. In a mine car, a truck unit comprising a pair of sill bars at each side, wheels between said sill bars and cross bars connecting said pairs of sill bars, the top surfaces of the sill bars at their ends being cut away to provide longitudinally extending supporting shoulders disposed below the top surfaces of the sill bars.
9. In a mine car, a truck unit comprising a pair of sill bars at each side, wheels between said sill bars and cross bars connecting said pairs of sill bars, the top surfaces of sill bars at their ends being cut away to provide longitudinally projecting supporting lugs below the top surfaces of the sill bars.
10. In a mine car, a truck comprising a pair of sill bars arranged at each side thereof, wheels disposed between each pair of sill bars, cross girts connecting said pairs of sill bars between the wheels and at the ends of the truck outside the wheels, said cross girts being disposed below the tops of the sill bars and being adapted to support a car floor, and inwardly extending floor supporting lugs formed integrally with the inner bars and disposed in substantially the same horizontal plane with said cross girts.
11. In a mine car, a truck comprising a pair of sill bars arranged at each side thereof, wheels disposed between each pair of sill bars, cross girts connecting said pairs of sill bars between the wheels and at the ends of the truck outside the wheels, said cross girts being disposed below the tops of the sill bars and being adapted to support a car floor, and inwardly extending floor supporting lugs formed integrally with the inner sill bars and disposed in substantially the same horizontal plane with said cross girts, said sill bars being cut away at their ends to form longitudinally extending supporting lugs and the end cross girts being carried by said lugs.
12. In a mine car, a truck unit comprising a pair of sill castings arranged at each side, wheels disposed between each pair of castings, and cross girts connecting the two pairs of castings, two of said cross girts being disposed at the ends of said castings outside the wheels and all of them being disposed below the top surface of the sill castings in a substantially common horizontal plane whereby to serve as floor supporting means.
13. In a mine car, a truck unit comprising a pair of sill castings arranged at each side, wheels disposed between each pair of castings, and cross girts connecting the two pairs of castings, two of said cross girts being disposed at the ends of said castings outside the wheels and all of them being disposed below the top surface of the sill castings in a substantially common horizontal plane whereby to serve as floor supporting means, said sill castings having their top surfaces cut away at their ends to form longitudinally projecting lugs and the end cross girts being carried by said lugs.
14. In a mine car, a truck unit comprising a pair of sill castings arranged at each side having their ends reduced to provide longitudinally projecting lugs below their top surfaces of the castings, wheels disposed between each pair of castings, and cross girts connecting the two pairs of castings, two of said cross girts being disposed at the ends of said castings outside the wheels comprising members angular in cross section having horizontal flanges supported on said lugs and vertical flanges extending downwardly at the ends of said lugs.
15. In a mine car, a truck unit comprising a pair of sill castings arranged at each side, wheels disposed between each pair of castings, and cross girts connecting the two

- 5 pairs of castings, two of said cross girts being disposed at the ends of said castings outside the wheels and all of them being disposed below the top surface of the sill castings in a substantially common horizontal plane whereby to serve as floor supporting means, said sill castings having their top surfaces cut away at their ends to form longitudinally projecting lugs and the end cross girts being carried by said lugs, and inwardly projecting floor supporting web members formed integrally with the inner sill castings and arranged in substantially the same horizontal plane with said cross girts and between the latter.
- 10 16. In a mine car, a truck unit comprising a pair of longitudinally extending sill castings arranged at each side, cross girts connecting said pairs of castings, wheels arranged between each pair of castings, a stub axle carrying each wheel and mounted in said castings, angle members secured to the outer sides of the outer sill castings of each pair and each having an outwardly extending horizontal flange, an outwardly extending floor plate secured to said flange and body side walls secured to said plate.
- 15 17. In a mine car, a truck unit comprising a pair of longitudinally extending sill castings arranged at each side, cross girts connecting said pairs of castings, wheels arranged between each pair of castings, a stub axle carrying each wheel and mounted in said castings, wheel hoods positioned over said wheels and secured to said castings, each of said hoods being provided with brace securing means, angle members secured to the outer sides of the outer sill castings of each pair and each having an outwardly extending horizontal flange, an outwardly extending floor plate secured to said flange and body side walls secured to said floor plates.
- 20 18. In a mine car, a truck unit comprising a pair of longitudinally extending sill castings arranged at each side, cross girts connecting said pairs of castings, wheels arranged between each pair of castings, a stub axle carrying each wheel and mounted in said castings, wheel hood castings positioned over said wheels and secured to said castings, each of said hoods being provided with brace securing means, angle members secured to the outer sides of the outer sill castings of each pair and each having an outwardly extending horizontal flange, an outwardly extending floor plate secured to said flange, body side walls secured to said plates, and side wall brace members secured to and extending between said hoods and side walls.
- 25 19. In a mine car, a truck unit comprising separately formed sill castings having inverted substantially U-shaped axle receiving recesses and axle saddle members for each of said seats comprising a member adapted to be secured to the casting and an integrally formed bearing member extending upwardly into the seat, said bearing member having a top surface forming a bearing seat for an axle.
- 30 20. In a mine car, a truck unit comprising separately formed sill castings having inverted substantially U-shaped axle receiving recesses and axial saddle members for each of said seats comprising a member adapted to be secured to the casting and an integrally formed bearing member extending upwardly into the seat, said sill castings having downwardly extending lugs adapted to project through openings in said saddle plate and to receive means for locking the saddle member in position.
- 35 21. In a mine car, a truck unit comprising sill castings having inverted substantially U-shaped axle receiving recesses, and axle saddle members for each of said seats comprising a base adapted to be secured to the casting beneath the U-shaped recesses and a bearing portion extending upwardly into the recess provided with a top surface forming a bearing seat for the axle.
- 40 22. In a mine car, a truck unit comprising sill castings having inverted substantially U-shaped axle receiving recesses, and axle saddle members for each of said seats comprising a base adapted to be secured to the casting beneath the U-shaped recesses and a bearing portion extending upwardly into the recess provided with a top surface forming a bearing seat for the axle, said U-shaped recesses having curved upper ends and forming with the bearing surface of said saddle members substantially two half-bearings.
- 45 23. In a mine car, a truck unit comprising sill castings having inverted substantially U-shaped axle receiving recesses, and axle saddle members for each of said seats comprising a base adapted to be secured to the casting beneath the U-shaped recesses and a bearing portion extending upwardly into the recess provided with a top surface forming a bearing seat for the axle, said U-shaped recesses having curved upper ends and forming with the bearing surface of said saddle members substantially two half-bearings, and means for attaching the base of said saddle member to the under-surface of the sill casting, said means comprising complementary lugs and openings upon said saddle member and the sill casting.
- 50 55 60 65 70 75 80 85 90 95 100 105 110 115 120 125 In testimony whereof I have hereunto set my hand.

GLENN E. EDMUNDSEN
